UNITED STATES PATENT OFFICE.

LADISLAUS DE DOORY, OF ALLSTON, MASSACHUSETTS.

SOAP-DISPENSER.

1,205,863.

Specification of Letters Patent. Patented Nov. 21, 1916.

Application filed December 21, 1914. Serial No. 878,211.

To all whom it may concern:

Be it known that I, LADISLAUS DE DOORY, a subject of the King of Hungary, and a resident of Allston, Massachusetts, have invented an Improvement in Soap-Dispensers, of which the following description, in connection with the accompanying drawings, is a specification, like characters on the drawings representing like parts.

- 10 This invention relates to dispensers for soap or other materials, and among other objects provides a device which is extremely simple and cheap in construction and effective in operation.
- 15 The character of the invention may be best understood by reference to the following description of an illustrative embodiment thereof shown in the accompanying drawing, wherein:
- 20 Figure 1 is a plan of an illustrative dispenser shown therein as embodying the invention; and Fig. 2 is a side elevation of the dispenser shown in Fig. 1.

Referring to the drawing, the illustrative 25 dispenser shown therein as embodying the invention comprises a support herein in the form of a bracket comprising a post 1 projecting from a base 3 and connected to resilient fork members 5, 5 having opposed 30 inturned ball-like terminals 7, 7 adapted to serve as bearings, as more fully hereinafter described. Fulcrumed on this support is a container 9 of glass or other appropriate material formed or pressed to present a 35 body having a forward and preferably upward projecting neck 11 provided with a discharge outlet 13. An important feature of the invention relates to the construction of this container whereby it may be freely 40 connected with or disconnected from said bracket. To accomplish this the container is pressed or otherwise formed to present seats or depressions 15 in opposite side walls thereof. To facilitate the introduction of 45 the fulcrum terminals 7 into these seats the body of the container is tapered rearwardly as at 17 and provided with guide grooves 18 leading to said seats. When it is desired to mount the container on its support its 50 tapered portion 17 is presented between the fulcrum terminals 7 and the container is thrust into the fork, thereby causing the terminals 7 to follow along said guide grooves until they come into registration 55 with the seats when they automatically spring into the same and support the con-

tainer. The bearing seats are located sufficiently high on the container so that the preponderance of the weight or the center of gravity of the container will be beneath 60 said seats and thus the container will tend normally to remain with its neck pointed upward as shown in Fig. 2.

When it is desired to discharge soap from the container it should be tilted forward by 65 a sharp quick movement. An important feature of the invention relates to the construction of the container whereby this movement may be readily effected. To this end the container is formed to present a 70 protuberance or portion 19 projecting forwardly beneath the neck 11. To discharge soap from the container the hand of the operator is presented to this protuberance and the tips of the fingers are pressed 75 against the same, causing the container to tilt and throw the neck thereof forwardly and downwardly toward the palm of the hand, thereby delivering a charge of soap 80 therein. The neck and protuberance preferably are so proportioned and spaced that when the tips of the fingers are engaging the protuberance and the container has been tilted forward the neck outlet will be at 85 the proper distance from the tips of the fingers to discharge into the palm of the hand.

In use there is a likelihood that the front 90 face of the container may have soap or water spattered thereon which would make the surface of the protuberance 19 somewhat slippery and render it difficult for the tips of the fingers to have a proper engagement therewith to tilt the container advantageously. To prevent such slipping 95 the forward face of the protuberance may have a series of horizontal ribs 21 pressed therein which may be positively engaged by the tips of the fingers. They also will permit the positive engagement of the fingers 100 at different distances from the neck of the container according to the length of the hand of the user.

By the device described, in mounting the 105 container on and dismounting the same from its support it is not necessary to make any preliminary adjustment of parts, but on the contrary these operations may be performed simply by a quick thrust of the container into the fork of the support in mounting 110 and a quick pull of the container from its support in dismounting.

It will be observed that the container is formed to present a base 20 by which it may be readily supported in upright position when not mounted on its bracket. At 5 such time the outlet 13 may be closed by a small cork 23, which may be withdrawn and thrown away after the container has been mounted in its bracket in readiness for use.

When the container is in its normal non-discharging position as shown in Fig. 2 the outlet 13 is above the level of the liquid in the container. Consequently air can readily pass into the outlet and occupy the space in the container above the level of the liquid. 10 When, however, the container is tilted to discharge, liquid therefrom the outlet is rocked forward and downward beneath the level of the liquid and some of the air in the container is forced out through the outlet, 15 thereby rarefying the air remaining in the container. When the container tilts back to its normal condition presenting its outlet again above the level of the liquid, air is insucked through the outlet to destroy the 20 vacuum created therein. This in-rush of air has an important advantage since it tends to draw any residual liquid remaining in the outlet back into the container and prevents its remaining in the outlet to dry and clog 25 the same. This action is assisted by the inclining of the outlet downward and inward 30 as well shown in Fig. 2 when the container is in its normal position.

If the container were truly spherical a 35 quick tilting movement thereof would tend to cause the same to slip around the body of the liquid contained therein owing to the inertia of the latter and a positive forced discharge would not be had from the container. The irregular form of the container disclosed herein is a desirable feature since it effectively contributes to a positive discharge of the liquid from the container. More specifically this is attained by the in- 40 wardly inclined wall of the container back of the corrugated surface 21 which on tilting of the container positively impels a surge of the liquid around the rear wall of the container upward and downward out 45 through the discharge outlet.

The containers are extremely cheap in construction and constitute the packages in which the soap is merchandized. One great objection to soap dispensers used heretofore 50 is the inconvenience of carrying a can or barrel of soap in stock and the filling of the container from time to time. By my invention this objection is obviated since the container in which the soap is sold constitutes a 55 part of the dispenser and after the soap therein is consumed the container is removed from the bracket and thrown away and a new full container is substituted therefor. 60 This practice is made possible because of the 65 extreme cheapness with which the glass con-

tainers can be made. There are no valves or plunger operated parts to rust, become clogged and get out of repair, but on the contrary the container is complete in one integral pressed glass piece.

While the device has been described more particularly in connection with its use as a soap dispenser it will be understood that perfume or any other material may be dispensed therefrom as desired.

Having described one illustrative embodiment of the invention without limiting the same thereto, what I claim as new and desire to secure by Letters Patent is:

1. A liquid dispenser comprising a container having a body provided with a neck projecting forwardly therefrom having a small port at the end thereof, and a protuberance projecting forwardly from said body beneath said neck having provision for positively impelling the liquid through said port on imparting a sharp forward tilting movement to said container.

2. A liquid dispenser comprising a container having a body provided with a neck projecting forwardly therefrom having a small port at the end thereof, and a protuberance projecting forwardly from said body beneath said neck formed to positively impel the liquid to and through said port on imparting a sharp, forward, tilting movement to said container, said protuberance presenting a ribbon or equivalent exterior surface to be engaged by and prevent slipping of the fingers of the hand in tilting the container.

3. A liquid dispenser comprising a container 9 having a forwardly projecting neck 11 with a small discharge port 13 at the end thereof, and a protuberance 19 projecting forwardly beneath said neck and formed to impel the liquid through said port on imparting a sharp, forward, tilting movement to said container, all of said parts being formed of one integral piece.

4. A liquid dispenser comprising a container having a body provided with a neck projecting forwardly therefrom having a small discharge port at the end thereof, a protuberance projecting forwardly from said body beneath said neck having provision for impelling liquid and air from the container through said port on imparting a sharp, forward tilt to said container, and a support pivotally connected to said container above the center of gravity thereof to automatically return the container to a position with its neck above the level of the liquid therein to allow air to rush into said container and drive residual liquid from said port.

5. A liquid dispenser comprising a body having a neck projecting forwardly therefrom with a small discharge port therein, a discharge impelling protuberance projecting from the bottom of said body beneath

said neck, a throat projecting a substantial distance into said body between said neck and protuberance and a curved unobstructed wall projecting from said protuberance to said neck; and means pivotally to support said body with its neck and protuberance normally projecting laterally in readiness for a discharging tilt of said body, said protuberance having provision for positively

forcing the liquid through said neck on the 10 discharging tilt of said body.

In testimony whereof, I have signed my name to this specification, in the presence of two subscribing witnesses.
